TIRE

Zoltan Mike, New Haven, Conn., assignor to The Armstrong Rubber Company, West Haven, Conn., a corporation of Connecticut

Filed June 26, 1968, Ser. No. 12,512

Term of patent 14 years

Int. Cl. D12—14

U.S. Cl. D90—20

FIG. 1

FIG. 2

FIG. 3

FIG. 1 is a perspective view of a tire showing my design;

FIG. 2 is a fragmentary plan view of a portion of the tread of the tire shown in FIG. 1; and

FIG. 3 is a transverse sectional view through the tire substantially on the plane indicated by the line 3—3 of FIG. 2.

It is to be understood that the tread pattern shown in FIG. 2 and in the foreground in FIG. 1 continues throughout the circumference of the tire.

The dominant features of the design are shown in full lines.

I claim:

The ornamental design for a tire, substantially as shown and described.
